UNITED STATES PATENT OFFICE.

BYRON J. C. BRUEGGER, OF LADYSMITH, WISCONSIN.

VACUUM DINNER-PAIL.

1,231,562.

Specification of Letters Patent.

Patented July 3, 1917.

Application filed January 28, 1916, Serial No. 74,937. Renewed May 12, 1917. Serial No. 168,314.

To all whom it may concern:

Be it known that I, BYRON J. C. BRUEGGER, a citizen of the United States, residing at Ladysmith, in the county of Rusk and State 5 of Wisconsin, have invented certain new and useful Improvements in Vacuum Dinner-Pails, of which the following is a specification.

This invention relates to an improved dinner pail and the principal object of the invention is to provide a dinner pail so constructed that a vacuum chamber may be provided in one portion thereof thus permitting certain articles placed in different parts of 15 the dinner pail to be maintained at different temperatures.

Another object of the invention is to so construct this dinner pail that the trays placed therein may each support the one, 20 above it, each tray being provided at its upper edge with an inner flange serving as strengthening means for the tray itself and as supporting means for the tray above it and to further so construct the bottom tray 25 above the vacuum chamber that the lower portion of this tray will form a portion of the vacuum wall of the vacuum chamber.

Another object of the invention is to so construct these trays that they will be easy to 30 clean, the inwardly extending flanges being so constructed that liquid will not be retained in the trays by the flanges.

Another object of the invention is to so construct this dinner pail that it will be 35 light but at the same time of a strong and durable construction thus preventing breakage or other damage.

This invention is illustrated in the accompanying drawings, wherein:

40 Figure 1 is a view showing the improved dinner pail in vertical section.

Fig. 2 is a transverse section taken along the line 2-2 of Fig. 1.

The dinner pail is provided with a body 45 portion or receptacle 10 having ears 11 with which the handle or bail 12 is connected, the ears 11 extending in spaced relation to the receptacle 10 so that the side walls 13 of the cover 14 may fit tightly upon the receptacle 50 without the ears 11 interfering with the placing of the cover upon the receptacle. This cover is provided with a neck 15 extending above the cover and serving as a carrier for a cup 16 which fits upon the neck as clearly 55 shown in Fig. 1. This receptacle is provided with an inner wall 17 which has its

upper edge portion soldered or otherwise tightly connected with the outer wall of the receptacle and from this point extends in spaced relation to the outer wall thus providing an air-tight vacuum chamber 18 which is positioned around and beneath the lower compartment 19. Studs or pins 20 extend from the outer wall and bottom of the receptacle 10 and engage the inner wall 17 60 to support this inner wall and also brace the outer wall against denting. A supporting ring 21 is secured to this inner wall within the compartment 19 and serves to support the tray 22 which fits in the inner 70 portion of the compartment 19 and has its upper edge provided with an inwardly extending flange 23. It should be noted that these flanges 21 and 23 are so formed that liquid will not be held within the tray or 75 compartment when the pail is washed and therefore danger of rust is prevented.

The articles which are to be retained either hot or cold are placed in the compartment 19 and tray 22 and the tray 24 80 is then put in place. This tray 24 is provided with a false bottom 25 providing an air-tight vacuum chamber 26 so shaped that it will fit tightly onto the seat 27 formed by the upper portion of the inner wall 17. 85 Therefore when the tray 24 is in place, the compartment 19 will be entirely inclosed by a vacuum wall thus retaining the contents of the compartment 19 and tray 22 at a predetermined temperature. A second tray 28 90

fits into the upper compartment 29 of the receptacle 10 and rests upon the tray 24, the tray 24 being provided with a flange 30 similar to the flange 23 to support the tray 28 and also brace the edge portion of the tray 24 and the tray 28 being provided with a flange 31 similar to the flange 30 and serving to brace the edge portion of the tray 28. It is of course, obvious that if desired the depth of the tray 24 could be 100 changed and a greater number of trays placed above the same, each tray being formed as is tray 28. Articles which are to remain at their normal temperature will be placed in the trays 24 and 28 and as the compartment 19 is inclosed by a vacuum, the heat or coldness of the articles placed therein will not affect the temperature of the compartment 29 and therefore will not affect the articles placed in the trays 24 105 and 28.

There has thus been provided a pail

which is so constructed that it will be very serviceable for carrying lunches and providing hot or cold drinks with the lunch or for keeping other articles warm.

5 **What is claimed is:—**

1. A vacuum dinner pail including an elongated receptacle, a tray mounted in the receptacle and adapted to be normally retained in spaced relation to the bottom and 10 inner periphery thereof, the upper margin of said tray being turned outwardly into snug engagement with the inner periphery of the receptacle to provide an air tight compartment around said tray, a second 15 tray mounted on the first mentioned tray and being completely housed within the receptacle, and a closure for the receptacle.
2. A vacuum dinner pail including a re-

ceptacle, a plurality of detachable trays concentrically arranged within the receptacle, 20 the lowermost of said trays having its upper margin bent outwardly obliquely and then acutely at right angles to provide a seat to accommodate another of the trays and to provide an air tight compartment between 25 said receptacle and the lowermost tray, and a flange mounted on the inner periphery of said lower tray to support a relatively smaller tray therein.

In testimony whereof I affix my signature in presence of two witnesses.

BYRON J. C. BRUEGGER.
